UNITED STATES PATENT OFFICE.

CHARLES HUSBAND, OF TAUNTON, MASSACHUSETTS.

DESIGN FOR CAR-LININGS, &c.

Specification forming part of Design No. 5,821, dated April 30, 1872.

To all persons to whom these presents may come:

Be it known that I, CHARLES HUSBAND, of Taunton, in the county of Bristol and State of Massachusetts, have invented or produced a new Ornamental Design for Car-Linings or various other articles of manufacture; and I do hereby declare the same to be fully represented in the accompanying drawings.

The design in question is exhibited in the rectangular space included between the dotted lines *a b c d*. It is also represented in reverse, either in whole or in part, against each

side of such space, in order to represent how it is to be carried out in covering a space of larger dimensions.

I claim as my invention or production—

The said ornamental design as shown in the annexed drawings and within the rectangular space included within the lines *a b c d*.

CHARLES HUSBAND.
